A. J. WHELAN

CLOTHES LINE PULLEY

Filed August 7, 1925

Patented Mar. 9, 1926.

1,576,387

UNITED STATES PATENT OFFICE.

AUGUSTIN J. WHELAN, OF JERSEY CITY, NEW JERSEY.

CLOTHESLINE PULLEY.

Application filed August 7, 1925. Serial No. 48,860.

To all whom it may concern:

Be it known that I, AUGUSTIN J. WHELAN, a citizen of United States, residing at Jersey City, in the county of Hudson and State of New Jersey, have invented new and useful Improvements in Clothesline Pulleys, of which the following is a specification.

This invention relates to improvements in clothes line pulleys.

10 The principal object of the invention resides in a means for laying a covering of fabric tape over a clothes line to prevent the soiling of washed clothing adapted to be hung thereon to dry, as it will be appreciated that dirt and dust readily accumulates upon the clothes line due to the fact that the line is exposed to the elements.

Another object of the invention is to provide a means for automatically winding the 20 tape about a reel upon longitudinal movement of the clothes line in one direction, when the line is not intended for use.

A further object is to provide a combined clothes line pulley and line protector which 25 is simple in construction, cheap of manufacture and easy of operation.

With these and other objects in view, the invention resides in certain novel construction and combination and arrangement of 30 parts, the essential features of which are hereinafter fully described, are particularly pointed out in the appended claims, and are illustrated in the accompanying drawing, in which:—

35 Figure 1 is a side elevation of my improved clothes line pulley shown in use with a portion of the casing broken away.

Figure 2 is a vertical longitudinal sectional view therethrough.

40 Figure 3 is a horizontal sectional view on the line 3—3 of Figure 1.

Figure 4 is a vertical transverse sectional view on the line 4—4 of Figure 1.

Figure 5 is a detail sectional view on the 45 line 5—5 of Figure 1.

It will be appreciated that clothes lines provided in the open are exposed to the elements and collect dirt and dust which is transferred to the washed clothes when hung thereon to dry. It is therefore the purpose 50 of this invention to apply a covering of fabric material to the line to protect the clothing or wash from becoming soiled when hung thereon.

55 Referring more particularly to the drawing, the reference numeral 10 designates a

hanger which is bent from a single piece of material to provide spaced parallel side walls 11, and an attaching eye 12 for use in supporting the device upon a hook or the like 60 13, which in turn is secured to a supporting structure. Although I have mentioned that the hanger is bent from a single piece of material, it will be appreciated that the hanger may be cast in a single piece if desired. Journalled for rotation between the side walls 11 are pulleys 14, there being four such pulleys shown in the drawing and which are so positioned to provide a loop 70 in the endless clothes line 15 and over which pulleys the line passes. The arrangement of the pulleys serves to provide spaced leads 16 in the clothes line and on which the clothes may be hung for drying purposes. A guide 17 extends between the side walls 75 and through which the line or cable passes in its movement from the rear upper pulley to the rear lower pulley.

One of the side walls 11 is provided with an opening 18 through which a reel of fabric 80 tape 19 may be inserted and said opening is normally closed by a removable cover plate 20. Journalled within the cover plate 20 and in the opposed side walls is a shaft 21 to which the reel is fixedly connected in a 85 manner now to be described. The tape is wound on a hollow shaft or spool 22, one end of which is provided with a square recess 23 for receiving a correspondingly shaped member 24 formed integral with the 90 shaft 21, it being understood that the shaft 21 passes through the hollow spool or shaft 22. The side edges of the wound tape frictionally engage the inner walls of the hanger whereby a tension is placed upon the spool 95 of tape to prevent the tape from being too rapidly paid out when applying the same to the clothes line.

From the foregoing description, it will be seen that the end of the tape is led from 100 the spool to one of the leads of the clothes line and held to the line by a clothes pin 24'. It will now be seen that by moving the clothes line in the direction of the arrow "A", the tape will be automatically paid out 105 from the spool and at suitable spaced intervals additional clothes pins may be applied for holding the tape in engagement with the line. The tape is of such width as to cover the top and sides of the line, so 110 that the wash hung thereon will not be subjected to direct contact with the line.

For the purpose of automatically rewinding the tape when the line is not in use, I provide a relatively large gear 25 fixed to one end of the shaft 21 and which meshes with a similar gear 26 fixed to a shaft 27 on which one of the pulleys 14 is keyed. The gears are disposed on the outer side of the hanger but are enclosed within a suitable casing 28. It will be seen that when the clothes line is moved in the direction of the arrow "B", the line passing over the pulley 14 which is fixed to the shaft 27 will transmit the rotation to the gear 26 and thence to the gear 25, thus imparting rotation to the spool in the direction of the arrow "C" which causes the winding of the tape. The clothes pins are removed as the same move to a position adjacent the hanger, thus holding the tape taut during the winding operation. When the tape has been completely wound, the entire spool is removed from the hanger by removing the cover plate and withdrawing the spool through the opening 18, as it will be appreciated that it would not be advisable to leave the spool of tape in the hanger where it will be exposed to dust and dirt.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In combination with a clothes line, pulleys over which the clothes line passes to provide spaced leads, a spool of tape disposed in alignment with said pulleys, and means for paying out said tape to cover

one of said leads of the line upon longitudinal movement of said lead in one direction, and means for automatically winding 45 said tape upon the spool upon longitudinal movement of said lead in the opposite direction.

2. In combination with a clothes line, pulley means over which the clothes line passes 50 to provide spaced leads, a spool of tape, and means for paying out said tape to cover one of said leads of the line upon longitudinal movement of said lead in one direction, and means for automatically winding said tape 55 upon the spool upon longitudinal movement of said lead in the opposite direction, said means including coating gears between said pulley means and said spool of tape.

3. A device of the class described comprising a hanger, pulleys journaled therein, a spool of tape, means for removably mounting said spool of tape within said hanger in alignment with said pulleys for rotation therein, and means for transmitting motion 65 from one of said pulleys to said spool of tape.

4. A device of the class described comprising a hanger having an opening in one of the side walls thereof, spaced pulleys rotatably supported thereby over which an endless cable is adapted to pass, a removable cover plate for closing said opening, a shaft journaled in one of the side walls of said hanger and said cover plate, a spool of 70 fabric tape removably supported by said shaft for rotation therewith, and means for transmitting motion from one of said pulleys to said shaft for imparting rotation to said spool of tape upon movement of said 75 pulley.

In testimony whereof I have affixed my signature.

AUGUSTIN J. WHELAN.
